UNITED STATES PATENT OFFICE.

WILSON E. SYMONS, OF SAVANNAH, GEORGIA.

DESIGN FOR A BRAKE-BEAM.

SPECIFICATION forming part of Design No. 35,105, dated September 17, 1901.

Application filed July 31, 1901. Serial No. 70,430. Term of patent 14 years.

To all whom it may concern:

Be it known that I, WILSON E. SYMONS, a citizen of the United States, residing at Savannah, in the county of Chatham and State of Georgia, have invented and produced a new and original Design for a Brake-Beam, of which the following is a specification.

This invention relates to brake-beams; and the object thereof is to provide a new, original, and useful design of this character.

In the present case the leading features reside in a hollow body which is substantially diamond-shaped in cross-section, with the corners rounded, said body tapering from its central portion toward its outer ends.

Minor features reside in disposing the central lugs at an inclination to the side walls, threading the terminal shanks, providing transverse openings or sockets through the body contiguous to its ends, and arranging openings in the walls.

In the drawings, Figure 1 is a perspective view of the new brake-beam. Fig. 2 is a side elevation of the same. Figs. 3, 4, and 5 are cross-sectional views taken at different points of the body to more clearly illustrate the configuration of the structure.

As will be seen by reference to the accom-

panying drawings, the beam is in the form of a hollow body 10, which is substantially 30 diamond-shaped in cross-section, with its corners rounded, as shown in Figs. 3, 4, and 5. The body tapers from its central portion toward its ends, and said central portion is provided with spaced lugs 12, which are located at an inclination to the side walls. The ends have projecting spindles 13, which are provided with terminal screw-threaded shanks 14 and a rib or feather 17. Transverse openings or sockets 15 are located in 40 the body contiguous to the inner ends of the spindles 13, and said body is furthermore provided with openings 16.

Having thus described my invention, what I claim as new, and desire to secure by Letters 45 Patent, is—

The design for a brake-beam as herein shown and described.

In testimony that I claim the foregoing as my own I have hereto affixed my signature in 50 the presence of two witnesses.

WILSON E. SYMONS.
